ELECTROMAGNETIC PRINTER

Lyne S. Trimble, North Hollywood, Michael J. Markakis, Playa Del Rey, Jerome L. Nishball, Los Angeles, and Merton C. Leinberger, Inglewood, Calif., assignors to The National Cash Register Company, Dayton, Ohio, a corporation of Maryland

Filed May 31, 1956, Ser. No. 588,450
16 Claims. (Cl. 346—74)

This invention relates to an automatic electromagnetic printer and more particularly to a novel means and method of forming and recording electrical signals defining the shapes of designated symbols in response to coded information received from an outside source.

The increasing prominence of the large-scale coding devices, such as the electronic digital computer, in business applications and the continuing use thereof in scientific fields has placed large emphasis on the development of high speed printing equipment to convert the binary coded language generally employed in the digital computer into a printed, visible record of intelligible symbols, such as the alphabetic, numeric, etc. characters, represented by the code. For practicality in these applications, it is also desirable that the record be printed at a speed approaching that at which input is fed from the external source. Accordingly, it is highly desirable to be able to print directly in response to electrical signals representing the characters, i.e., to form the characters by magnetically recording signals defining the shape thereof. It is also very desirable that the different symbols or characters formed on the record in this manner be clearly distinguishable from each other and that confusion due to overlap of individual characters, intermingling of lines, meaningless spaces, etc. be eliminated by properly synchronizing and controlling the operations of the printer.

It is thus an object of this invention to provide a high speed electromagnetic printer possessing the aforesaid attributes to a degree which makes its use in an electronic computer data processing system devoted to billing, inventory control, etc., or in conjunction with equipment for plotting, teletyping, chart recording, etc., highly appropriate.

It is another object of this invention to provide a simple, reliable means for timing and directing the electrical signals so as to cause recording of the characters in the proper positions of the line of the medium.

It is a further object of this invention to provide a printer capable of accepting binary coded information and immediately recording the characters represented thereby to form successive lines of legible information on a medium useful for business purposes.

Another object of the invention resides in the provision of means to encode information received from the source equipment employing, in the preferred embodiment, a substitution code easily and rapidly changed by the operator of the printer without affecting the operation of the source equipment. A feature associated with this object is an unlimited number of character matrices (configurations), the number of characters contained in each matrix being a function of the number of different meaningful codes which can be set up as inputs to the printer. Thus the substitution code may arrange to affect the distribution of characters in the matrix and consequently the character actually printed in response to a code transmitted by the computer.

Other objects and many of the attendant advantages of the present invention will become readily apparent as the same become better understood by reference to the preferred embodiment detailed in the following description and accompanying drawings in which:

2

FIG. 1 is a perspective view showing the overall arrangement of the components for performing the printing process.

FIG. 2 is a simplified block diagram of the electrical circuits associated with the converter and recorder units of the printer.

FIG. 3 is a plan view of the surface of the drum of the recorder showing the arrangement of the recording projections thereon.

10 FIG. 4 is a cross-section of a portion of the drum surface showing the two types of projections provided thereon.

FIG. 5 is a cross-sectional view of the drum of the recorder showing the path of the magnetic field for recording.

15 FIG. 6 is a schematic diagram of the wave-shaping circuitry provided for generating timing signals.

FIG. 7 is a block diagram of the character counter of FIG. 2.

20 FIG. 8 is a block diagram of the sweep counter of FIG. 2.

FIGS. 9 to 12 are diagrams of flip-flops N1, P1, Q1, and M1 together with the logical equations defining the grid triggering networks therefor.

25 FIG. 13 is a graph of waveforms for explaining the operation of the N1 flip-flop.

FIGS. 14 and 15 show the networks for generating propositions used by the character counter and print control circuit.

30 FIG. 16 shows the network of the transfer circuit of FIG. 2 which generates signal R.

FIG. 17 shows the network for generating the sum S_a used by the transfer circuit.

35 FIG. 18 is a schematic diagram of the cathode ray tube horizontal deflection circuitry.

FIG. 19 is a schematic diagram of the cathode ray tube vertical deflection circuitry.

40 FIG. 20 is a plan view of a preferred form of mask indicating how the individual characters areas thereof are identified by row and column.

FIG. 21 is a table showing how the code set up in the computer output register flip-flops L1 to L6 select the desired character area of the mask.

45 FIG. 22 shows a portion of the cathode ray tube screen and how an area thereof corresponding positionally to a character area on the mask is scanned by the electron beam.

50 FIG. 23 is an enlarged view of the portion of the mask of FIG. 20 showing how the horizontal and vertical deflection circuits effect coverage of the character area by the cathode ray tube electron beam.

FIG. 24 is an enlarged view of a portion of the mask representing the character area for the character "A."

FIG. 25 is an enlarged view of characters as printed on the paper by the system of the invention.

55 FIG. 26 contains graphs of the phototube output voltage as the character "A" is scanned.

FIG. 27 is a schematic diagram of the phototube signal shaping circuitry.

60 FIG. 28 is a schematic diagram of the circuitry for selecting and driving the recording bars.

FIG. 29 is a schematic diagram of the circuitry used to energize the paper move relays.

65 FIG. 30 is a graph depicting the activity of printer components with relation to successive revolutions of the drum.

FIG. 31 shows a schematic view of the dust inker and drier.

70 FIG. 32 shows the paper take-up mechanism in perspective.

The printer of the present invention will first be generally described by reference to FIG. 1, showing an over-

all view of the printer in perspective, with emphasis on the physical arrangement of its component parts. As will be clearly pointed out, the principle employed by the present invention to produce visible and legible print at high speed is basically magnetic, although under electronic control.

Thus codes comprising groups of electrical signals originating from an external digital source, such as a digital processor, are set up on conductors of cable 103. These coded signals are transmitted in response to timing signals C_c generated as a result of association between magnetic head 108b and character timing track #2 provided on rotating drum 101. The groups of coded signals are received serially by converter 300 which serves to convert each group to deflection potentials for positioning electron beam 146 of cathode ray tube 132. Converter 300 also provides additional deflection potentials in response to timing signals C_s generated by the association of magnetic head 108a with the sweep timing track #1. This additional deflection causes beam 146 to scan a small area of screen 134 of tube 132. Mask 135, containing a plurality of character-defining areas, one corresponding to each area of screen 134 scannable by beam 146, passes the uninterrupted portion of the illumination caused by the beam, onto phototube 139, which converts the modulated light into a series of electrical pulses. Each pulse series thus produced uniquely defines a character.

Converter 300, in its preferred form, is capable of recognizing a maximum of 64 different signal groups from the source to accordingly produce 64 different types or kinds of pulse sets or trains. Each pulse train is utilized in recorder 301 to energize one or the other of electromagnetic recording heads, designated bar #1 and bar #2, positioned adjacent magnetically sensitized paper 114. Selection between bar #1 and bar #2 is made in accordance with the positional location on a line of paper 114 to be recorded with the character. Bars #1 and #2 are so aligned that the magnetic field issue therefrom is directed to perpendicularly pass through paper 114; and in order to confine the magnetic field to the position on the line of paper where the character is to be recorded, means are provided to concentrate the field for each character section along a succession of narrow parallel paths extending longitudinally on paper 114 a distance approximately equal to the height of the print desired. The means so provided comprises a plurality of magnetically conductive recording projections 107 attached to the surface of rotating drum 101 along a helical path. Thus, as the drum revolves, these projections successively traverse one of the bars #1 or #2 and cause a recording to be made on the paper 114 in accordance with the electrical signal which is energizing the bar at that time. Thus a serial recording of the signals representing each character section is placed side by side on the same line of paper 114 by successive passes of projections 107 on drum 101. When a complete pulse train is recorded in this fashion, a latent magnetic image of a character is formed on the paper 114. In order to synchronize the receiving of pulse trains from converter 300 with the passing of the proper projections 107 under the bars #1 or #2, the start of a printing cycle of the drum is made with reference to timing signals C_g generated by head 108c associated with cycle timing track #3.

During the time that paper 114 is being printed, it is stationarily positioned between drum 101 and bars #1 and #2. Upon completion of the printing of one line of sixty characters, paper 114 is moved by action of a pair of relays 120 and continuously rotating shaft 115 so as to be positioned for printing the next line.

Paper 114 is then passed through inker 302 wherein the latent image is made visible. Inker 302 comprises dusting chamber 179 which receives an air stream by way of duct 180a. This air stream was previously mixed with resin-coated magnetizable particles as it passed through

reservoir 198; thus, upon expanding in dusting chamber 179, it produces a low velocity cloud 181 of black magnetizable resin-coated particles which surrounds paper 114. A high density of particles is attracted to the surface of paper 114 where the characters have been magnetically formed. The paper is then passed adjacent infra-red lamp drier 182 which employs heat to melt the resin coating of the particles to a gluelike consistency which, upon cooling, hardens and seals the particles to paper 114, thereby contributing permanence to the characters. Take-up mechanism 202 operates to provide tautness to the paper as it is conveyed through inker 302.

Having generally described the printer arrangement, reference will now be made to FIG. 2, showing a simplified block diagram of the functionally prominent electrical circuitry and devices which cooperate to produce the latent character images, together with relevant units of a digital computer, selected as an input device therefor.

20 The operating system of computer 90, contemplated for use with the preferred embodiment of printer 100 of the present invention, is well known in the art as providing for sequencing through step operations in accordance with a prescribed program of instructions. Step operations in the flow may be controlled by a program counter 91. This technique conveniently sets up outputs from program counter 91 unique to the program; and, for an instruction which directs transmission of stored information to printer 100, for instance, a step operation may cause the corresponding output of program counter 91 to be conveyed to printer 100 as a "start" signal S on line 93. Start signal S energizes electrical networks in print control circuit 124, which, in turn, activates character counter 125 to count, thereby 25 readying printer components for the receipt of coded information. Selected count outputs from character counter 125 cause transfer circuit 128 to signal readiness to print by means of a "ready" signal R sent to computer 90 by line 94. On receipt of the ready signal R, computer networks control the program counter 91 to cause computer 90 to enter a portion of its flow which sequentially resets output register 92 sixty times, each 30 reset in response to an additional ready signal R sequentially received from transfer circuit 128. Each setting of output register 92 corresponds to a coded information character to be printed on one line of paper 114. When the last (60th) character of the line is transmitted and printed, computer 90 may automatically repeat these 35 step operations to provide for printing of further lines. 40 When the computer memory has been depleted of all stored information to be printed at this time, computer 90 enters other portions of its program. Thus it is seen that character code transmission from computer 90 to printer 100 is a serial process which is synchronized by 45 50 55 5 intercommunicating signals S and R.

It has been pointed out that the code corresponding to the next character to be printed is set up by computer 90 in its output register 92, here comprising, in the main, flip-flops L1 to L6. This code may represent characters of any desired nature: alphabetic, numeric, symbolic, punctuation, etc. In the embodiment to be described, up to 64 different character codes may be employed. The codes are received by deflection circuits 131 and 136 by way of lines 95 and 96, respectively, and converted to deflection voltages for electron beam 146 of cathode ray tube 132. The deflection voltages direct beam 146 to a location on phosphorescent screen 134 of tube 132 and additional deflection voltages, generated by deflection circuits 131 and 136 in response to sweep timing signals C_s , cause beam 146 to repetitively sweep vertically at spaced horizontal positions to form a raster 133. Beam 146 thus covers a different rectangular area on screen 134 for each character code. The sweep is from top to bottom of raster 133 and ten successive 60 65 70 75 80 85 90 95 98 99 sweeps are made, positioned horizontally from left to

right in accordance with outputs from sweep counter 126, which generates ten different count outputs T_0 , T_1 , . . . T_9 . Positioned adjacent screen 134 such that their surfaces adjoin is a mask 135, opaque over most of its area, but containing translucent portions shaped to conform with up to 64 different characters, which correspond to the 64 different character codes which may be received from computer 90. For each character code received, the area covered by raster 133 conforms to the area of mask 135 which may be occupied by a corresponding character. This arrangement thus causes light to be transmitted through mask 135 as pulses of various durations, as beam 146 sweeps successive sections of the selected area. The light pulses, which occur in sets of light pulse trains and which define the form of the character, impinge on sensitized cathode 141 of phototube 139, appropriately stationed opposite screen 134. Phototube 139 converts the impinging light energy to corresponding electrical pulse signals which are amplified and shaped by signal shaping circuit 158 and employed to energize one or the other of the magnetic recording bars, designated bar #1 and bar #2, as selected by bar selector circuit 129. Recording means provided by the invention comprise a continuously rotating drum 101 containing the small recording projections 107 of magnetic material arranged in a helical path around the drum circumference. Recording bars #1 and #2 are in close proximity to drum 101 such that the direction of bar magnetic flux lines is toward drum 101. Magnetizable paper 114 is intermittently fed, by means of paper move relays 120 as controlled by paper move circuit 157, to pass between the bars and drum 101 such that paper 114 is stationary when bars #1 and #2 are recording, and moving to position a new line for printing after 60 characters have been recorded. Drum recording projections 107 serve as field concentrators to heavily magnetize paper 114 in lines perpendicular to its surface. The preferred arrangement of recording projections 107 is in groups, each group accomplishing the formation of a single character at a particular area on a line of paper 114. The 60 characters on a line are formed by coincidence of electrical pulses in bars #1 or #2 with the successive traversal of the corresponding recording projections 107 between drum 101 and paper 114. In summary, a magnetic recording of a character is formed at a position on a line on paper 114 by a coincidence of electrical signals in recording bar #1 or #2 and the traversal thereunder of the group of field concentrator projections 107 on drum 101 corresponding to the positional location on the line.

To provide the proper timing intervals for all operations of the printer, the three repetitive clock pulse signals C_s , C_c , and C_g are generated as outputs from shaping circuits 110 from inputs received from magnetic heads 108a, 108b, and 108c sensing the passage of projections 106 arranged on drum 101 in three circumferential tracks, designated the sweep timing track #1, the character timing track #2, and the cycle timing track #3, respectively.

Drum 101, shown in perspective in FIG. 2 and in plan view in FIG. 3, is in constant rotation in the direction indicated by the arrow on the right end thereof by a motor (not shown) or the equivalent, operating by way of drive 102. Drum 101 is cast of a material, such as aluminum, having properties with little or no effect on magnetic fields, and in the preferred embodiment is about 12 inches in diameter and 12 inches wide. Protruding from circumferential surface 105 of drum 101 are a plurality of projections extending outwardly to a height of approximately $\frac{1}{8}$ inch. These projections are formed of magnetic material and, in physical configuration, are of two types, as shown in FIG. 4. Each timing projection 106 is similar to a gear tooth, being about $\frac{1}{4}$ inch long and positioned, as shown, with the longitudinal dimension perpendicular to the direction of motion of rotating drum 101. Reference to FIG. 3 will show that

350 timing projections 106 are provided on the rightmost track #1. It is to be noted that the projections 106 in this track are arranged in groups of 10, the projections in each group being evenly spaced. The separation 270 between groups slightly exceeds the separation 271 between projections 106 within a group. Reference to FIG. 3 also shows that 35 timing projections 106 are evenly spaced about central track #2. It is to be noted that the distance 272 between a projection 106 of track #2 and the last preceding projection 106 of a group of track #1 is equal to the separation 271 between projections 106 within a group of track #1. Thus a projection 106 of track #2 is displaced a slight distance 273 ahead of the first projection 106 of a group on track #1. Further, it is noted that there is only one projection 106 in track #3 and it is located a slight distance 274 below a projection 106 of track #2. The reasons for this arrangement of projections 106 are reserved for later discussion.

20 Continuing to regard FIG. 3 in conjunction with FIG. 4, it is seen that recording projections 107, which are cylindrical in elevation, are disposed around the periphery of drum 101 along a helical path. The rightmost portion of the helical path contains 350 recording projections 107; this portion of the helical path is effective during the first revolution of the printer cycle. The leftmost portion of the helical path contains 250 recording projections 107. This latter portion of the helical path is effective during the second revolution of the printing cycle. As will be described hereinafter, each printing cycle includes two revolutions of the drum and defines the time during which a line on the paper is printed. In the preferred form, the recording projections 107 are arranged in groups of ten, as shown, each 25 group corresponding to a character to be printed, and each group is laterally displaced from its neighbors by a space 275, as shown. Each group effects the printing of one character and the lateral spacing 275 between groups provides for spacing between characters. The 30 60 groups effect the printing of 60 characters on one line of paper, the groups being identified in FIG. 3 in accordance with the character designations. It is further noted that each recording projection 107 in the helical path is laterally aligned with one of the timing projections 106 on track #1, and that the last group (corresponding to the 60th character) ends short of the position of projection 106 of track #3 by a distance equivalent to that required by ten groups. Reasons for this arrangement will be given at a later time.

35 It may be noted here that, as shown in FIG. 4, in the preferred arrangement, timing projections 106 are formed by an acid etching process on a ferrous metal band 329 which is then forcibly pressed in place over a recessed portion 330 at the right end of drum 101. Recording 40 projections 107 are press fitted into holes 331 appropriately drilled in drum 101.

45 Returning to FIG. 2, as drum 101 revolves, identical magnetic heads, stationarily positioned close to surface 105, sense the passage of recording projections 106 in each of the tracks. For example, head 108a is thus associated with track #1. As shown in FIG. 6, head 108a is of the reluctance type having a permanent magnet 280 with an air gap 281 containing a pointed stylus 282 on which is wound a coil 283. Head 108a operates such 50 that a change in reluctance of gap 281 due to proximity 55 between the apex of a timing projection 106 and magnet 280 generates an electrical signal in coil 283. The signal is carried by line 109, for the exemplary case, to shaping circuit 110 (FIG. 2) where, as will be shown, it is caused 60 to serve as a basis for generating pulses C_s and C_s' , employed for timing purposes. Pulses C_c and C_g are similarly generated using the other two tracks #1 and #3, and are also employed for timing various operations of printer 100. It may briefly be noted with reference to 65 70 75 these pulses, however, that for each drum revolution,

cycle pulse C_g is generated once, character pulse C_c is generated 35 times, and sweep pulse C_s is generated 350 times; further, that due to the spacing of projections 106 pulse C_g is generated slightly in advance of a pulse C_c and that pulses C_c are generated slightly in advance of the first pulse C_s of a group. It is with reference to these pulses that printer components are synchronized. Thus it follows that sequential operations of printer 100 are in synchronism with drum revolutions.

Also as drum 101 revolves, the recording projections 107 traverse the area suspended by the pair of positionally fixed, identical magnetic heads, labelled bar #1 and bar #2; the projections effective during the first revolution of a cycle traverse beneath bar #1 and a portion of bar #2, and those effective during the second revolution of a cycle traverse beneath bar #2. These bars, shown in perspective in FIG. 3 and in cross-section in FIG. 5, are of ferrite material or the like, shaped with a rectangular portion 111 surmounting a triangular portion 112, a coil 113 being wound on a recess in the former. Apex 153 of triangular portion 112 is ground flat, the width being slightly less than the distance between projections 107. These bars comprise electromagnets, which, when energized by coil current, due to the orientation of apex 153 of triangular portion 112, concentrate their magnetic fields towards surface 105 of drum 101. A more intense concentration of field occurs, of course, in the interstice between apex 153 and the apex of a passing projection 107. It is this latter concentration of field that contributes to the formation of a character on paper 114. It is noted that, the width of apex 153 being less than the separation between projections 107, only one projection 107 can be directly below a bar at a time and thus be effective to record. Further, since recording is accomplished by a distortion of field from a bar by a projection 107, the width of apex 153, in effect, limits the height of a character. It may also be noted at this time that a line of 60 characters is printed in two revolutions of drum 101 on paper 114, stationarily positioned during recording between the bars and surface 105, the first revolution causing the printing of the first through the 35th characters by cooperation of the recording projections 107 and both bars, and the second revolution causing the printing of the 36th through the 60th characters by cooperation of the recording projections 107 and bar #2. It may be pointed out that the second revolution includes a ten character print time delay during which paper 114 may be shifted for printing a next line.

It may be again noted that the last five characters, the 31st to 35th, recorded may be regarded as an overlap. It has been determined that the field resulting from electrical energization in a bar extends beyond the area of the bar and, particularly, into the area of the other bar a distance of approximately thirty times the distance between recording projections 107. Thus, regarding FIG. 3, if the right end of bar #2 were to be traversed by recording projections 107 during the recording of the 1st, 2nd, and 3rd characters, the field of bar #1 extending below bar #2 would produce a duplicate recording of these characters at the area of paper later to be recorded by energizing bar #2 at the beginning of the second revolution of the printing cycle. The overlap provides lateral displacement at the right end of bar #2 of 50 times the lateral distance between recording projections 107 at the right end of bar #2. Thus, during the recording of the first three characters by bar #1, bar #2, not having field concentrators to cooperate therewith, produces no recording.

It has been pointed out in connection with a discussion of drum 101 that three independent clock signals, designated C_s , C_c , and C_g , of pulse form, are generated by shaping circuits 110 employing the output of heads 108a, 108b, and 108c (FIG. 2). Shaping circuits 110 are identical and will now be described with reference

to that shown in FIG. 6, which generates pulses C_s and C_s' .

As a timing projection 106 moves past head 108a, electrical pulse 168 appears on line 169, by which the head 5 is coupled to two-stage amplifier 164. The output of amplifier 164 comprises pulse 169, a magnified in-phase replica of pulse 168, and is fed to trigger circuit 165, comprising tubes 170 and 171. Normally, due to the grid biasing arrangement and common cathode resistor 172, tube 170 is cut off and tube 171 is conducting heavily. Pulse 169, being positive with reference to the ground return of tube 170, at some point of its leading edge, causes tube 170 to start conducting. The resulting decrease in plate potential of tube 170 is impressed on 10 the grid of tube 171 through network 332, and the increased voltage drop across common cathode resistor 172 causes a steep rise in the plate potential of tube 171. This condition is maintained while the amplitude of pulse 169 is more positive than the potential that caused the 15 condition.

Similarly, the conduction in tube 170 is sharply cut off at a point on the trailing edge of pulse 169. Thus the output of trigger circuit 165 is squared pulse 173 having a time duration approximately equal to that between triggering amplitudes of pulse 169. Pulse 173 is 20 coupled to one-shot 166, which, being in a condition such that tube 174 is normally cut off and tube 175 is normally conducting, produces in this case a pulse output corresponding to the leading edge only of pulse 173. The output, pulse 176, is in phase with pulse 173 and, as is well known, has a duration as established by the 25 time constant of the one-shot circuitry, here approximately 5 microseconds. Pulse 176 is conveyed to two-stage driver-amplifier 167, where it is amplified, inverted, and clamped between the potentials +100 v. and +125 v. to give the output pulse C_s' which, in tube 178, is also amplified, inverted, and clamped between +100 v. and +125 v. to give the output pulse C_s .

It has been pointed out that the other clock signal 30 pulses C_g and C_c are also generated in this manner. It will be noted from FIG. 2, however, that the primes of these pulses are not employed.

As shown in FIG. 2, two binary counters are embodied 35 in the printer, character counter 125 and sweep counter 126, the former producing 61 discrete outputs and the latter producing 10 discrete outputs. The means employed in the counters to produce these outputs are well understood in the art and will be but briefly presented here.

50 It has been indicated that selected count outputs from character counter 125 cause a signal R, signifying that the printer is ready to receive a character code, to be transmitted to the computer. More broadly, as will be made apparent, this counter establishes time intervals for 55 all operations of printer 100.

Character counter 125 is shown in block form in FIG. 7 to comprise seven flip-flop circuits, A1 to A7, coacting by virtue of diode network 127 to produce 61 outputs, S_0 to S_{59} and S_x . The count output of character counter 60 125 is arranged to change on receipt of input pulse $N_1 C_c$ from print control circuit 124 (FIG. 2). With momentary reference to FIG. 3, it may be noted that the outputs $S_0 \dots S_{34}$ occur during the first revolution of a printing cycle as the first 35 characters are being printed, the outputs $S_{35} \dots S_{59}$ occur during the second revolution of a printing cycle as the remaining 25 characters are being printed and the output S_x occurring at all other times, i.e., during the ten character-time hiatus reserved for shifting paper 114 from printing the next line (following the count S_{59}) and during quiescence as defined hereinafter. Selected outputs from character counter 125 are fed as inputs to print control circuit 124, transfer circuit 128, and bar selector circuit 129, to be discussed later.

70 Referring again to FIG. 2, sweep counter 126 oper-

ates through its counting cycle as the group of 10 projections 107 corresponding to a character traverses past bar #1 or bar #2. The outputs from sweep counter 126 are fed to horizontal deflection circuit 131 wherein they act to position electron beam 146 of cathode ray tube 132 to permit scanning of successive sections of raster 133. Sweep counter 126 is shown in block form in FIG. 8 to comprise four flip-flop circuits, B1 to B4, coacting by virtue of diode network 130 to produce 10 sequential output counts $T_0, T_1 \dots T_9$, respectively, the output being arranged to change on receipt of successive pulses C_s .

Table I summarizes the activity of sweep counter 126. It may be observed that the output counts have been selected with regard to symmetry of the states of the flip-flops in combination. The reasons for this type of selection will be made apparent in connection with a discussion of horizontal deflection circuit 131.

TABLE I
Sweep counter 126

Sequential Count Designation	Flip-Flops			
	B1	B2	B3	B4
T_0	0	0	1	1
T_1	0	1	0	0
T_2	0	1	0	1
T_3	0	1	1	0
T_4	0	1	1	1
T_5	1	0	0	0
T_6	1	0	0	1
T_7	1	0	1	0
T_8	1	0	1	1
T_9	1	1	0	0

Still with reference to FIG. 2, it is seen that intercommunication between computer 90 and printer 100 components is by lines 93, 94, 95, and 96 carrying three types of signal.

The first of these signals is "start" pulse S, on line 93, which is generated as an output count of program counter 91 when the first operation in the program "read out to printer" is accomplished, and is received by print control circuit 124. Print control circuit 124 is energized by the start pulse S to cause character counter 125 to change its output from the static count S_x and sequence through its count cycle. The outputs S_0 to S_{58} and S_x of character counter 125 are conveyed to transfer circuit 128 wherein they are logically multiplied by output N_1 of flip-flop N1 and pulses C_c . The resulting signal, designated for simplicity as pulse R, is sequentially transmitted by line 94 to program counter 91, and is effective to advance the program whereby output register 92, comprised mainly of flip-flops L1 to L6, is sequentially set up with codes representing characters for which printing is to be done. Thus it is noted that flip-flops L1 to L6 are reset with a new character code only in response to receipt by program counter 91 of a pulse R, transmitted by transfer circuit 128 only when printer 100 is ready therefor, as for instance, after the printing of a prior character has been completed. For the printing of one line of 60 characters, sixty R pulses are transmitted. The pulse C_c , after the transmission of the last pulse R, is identified by print control circuit 124 which acts to stop the printing process and energize paper move circuit 157 to cause paper 114 to be shifted ahead for printing of the next line. The last pulse R is also identified by program counter 91 which acts to cause computer 90 to re-enter the first operation in the program "read out to printer" if additional character codes are available in the computer memory, or, otherwise, to enter a routine in the program which identifies the next command to be executed.

The third type of signal, transmitted on lines 95 and 96 from output register 92 on receipt of pulse R from transfer circuit 128, comprises the binary code represent-

ing information stored in the computer memory. Up to 64 codes can be handled in the preferred embodiment of the invention. In response to each pulse R that is received, computer 90 sets up flip-flops L1 to L6 to represent the code of a character. Thus the 12 output lines from flip-flops L1 to L6, labelled in FIG. 2 as $L_1, L_1', L_2, L_2', \dots L_6, L_6'$, in combination, represent the code of a character. Six of the lines, combined as line 96, are energized by the outputs from flip-flops L1, L2, and L3, and are received by vertical deflection circuit 136. Six of the lines, combined as line 95, are energized by the outputs from flip-flops L4, L5, and L6, and are received by horizontal deflection circuit 131. Deflection circuits 131 and 136 operate to deflect electron beam 146 of cathode ray tube 132 to impinge on tube screen 134 at the area, one of the 64 character areas, determined by the code presently set up in flip-flops L1 to L6, and, additionally, provide deflection voltages comprising 10 different horizontally deflecting potentials and 10 vertically deflecting sweep potentials, respectively. The states of flip-flops L1 to L6, presented in FIG. 21, will be shown to select a character area of mask 135 by row and column, in connection with a discussion of that figure hereinafter.

25 The present printer employs the flip-flop type of bistable state circuit for control of various of its operations, the flip-flops being designated as follows:

Flip-flop Q1 defines the time interval between receipt of start pulse S from computer 90 and the printing of 30 the last character of a line.

Flip-flop N1 defines the two revolutions of drum 101 which comprise the printing cycle.

Flip-flop M1 controls switching between the two recording bars #1 and #2.

35 Flip-flop P1 controls the energization to paper move relays 120.

Flip-flops A1 to A7, inclusive, function, as shown in connection with FIG. 7, as binary stages for character counter 125.

40 Flip-flops B1 to B4, inclusive, function, as shown in connection with FIG. 8 and Table I, as binary stages for sweep counter 126.

The nomenclature used to express terms of logical equations which are employed to describe the activity of 45 circuitry will next be outlined. Terms in such equations are generally based on the states assumed by bistable circuits having two inputs and two outputs, such as flip-flops, the outputs being clamped at the preferred logical potentials of +125 v. and +100 v. These circuits will 50 have designations comprising a letter-number combination. For example, flip-flop N1 is triggered into a true state, i.e., output N_1 is at +125 v., by an input n_1 ; and into a false state, i.e., output N_1' is at +125 v., by an input n_1' . When one output of the circuit is at +125 v., 55 the other output is at +100 v. Networks are arranged to respond to these voltages, which may thus be considered to represent the binary values "one" and "zero," respectively.

As shown in FIG. 9, a schematic diagram of the preferred form of flip-flop, here designated flip-flop N1, the 60 circuit includes tubes 234 and 235 intercoupled by networks such as network 237. In each tube, the plate is connected to a +225 v. supply through a resistor such as resistor 238; the grid is connected to a -300 v. supply through a resistor such as resistor 239, and the cathode is grounded. Inputs n_1 and n_1' to the grids of tubes 234 and 235 are from "and" gates 240 and 241, respectively, and are differentiated by networks such as network 242 and clipped at the +3 v. level by diodes such as diode 243. Thus only negative pulses are effective on the grids. For each tube, also, the plate is clamped at the potentials +100 v. and +125 v. by diodes such as diodes 244 and 245.

Assuming that flip-flop N1 is false, i.e., output N_1' is 75 at +125 v. and output N_1 is at +100 v., a negative pulse

11

applied to the grid of tube 235 will cut this tube off, thereby causing output N_1' to drop to +100 v. and output N_1 to rise to +125 v. This pulse is provided by output n_1 from "and" gate 241, occurring when all of the inputs N_1' , Q_1 , M_1' , and C_g are at +125 v. and pulse C_g abruptly falls to +100 v. The differentiation of the fall produces a pulse which acts as the requisite negative-going trigger. Thus, the equation for triggering flip-flop N_1 true may be written, in logical product form, in accordance with well-known principles of Boolean algebra, as

$$n_1 = N_1' Q_1 M_1' C_g$$

and is shown, together with the n_1 equation, below the circuit.

The curves of FIG. 13 illustrate the triggering of flip-flop N_1 in accordance with the n_1 equation. Line I represents pulse $M_1' C_g$, which, it will be recalled, occurs once for each revolution of drum 101 and is the output of the logical "and" gate shown in FIG. 15. Line II shows output Q_1 of flip-flop Q_1 , which, in accordance with the n_1 equation, is required to be at +125 v. in order that flip-flop N_1 may be triggered true. It will be shown that flip-flop Q_1 is set true by "start" pulse S received from the computer, in this case at a time prior to the generation of a pulse C_g , and that, for this condition, flip-flop M_1 is false, thereby making bar #1 available for recording. Thus "and" gate 241 (FIG. 9) is arranged to make the true input of flip-flop N_1 responsive to C_g trigger pulses provided the flip-flop is in the false state. In line III this latter provision is shown to be met. It is thus the pulse $M_1' C_g$ that determines when an effective true input n_1 (line IV) will be generated. However, flip-flop N_1 will be triggered true only by a negative-going pulse applied to its true grid. This pulse occurs, as shown in line V, when input n_1 sharply drops to a low potential at the fall of pulse $M_1' C_g$. Thus, as line VI shows, output N_1 swings to +125 v.

For other bistable circuits, resort will be made to block diagrams to represent the schematic form, as illustrated in FIGS. 10, 11, and 12 for flip-flops P_1 , Q_1 , and M_1 , and the Boolean equations and networks which define when and how the circuit is to change will be shown therewith.

Logical sum networks, such as "or" gate 246 of FIG. 12, are also well known to operate to produce an output, in this case of +125 v. on line 247, when at least one of the inputs, here terms N_1' and S_{59} , is at +125 v., otherwise the output on line 247 is at +100 v. The output of "or" gate 246 may thus be represented as a logical sum term $(N_1' + S_{59})$, which is seen to be an input to an "and" network 248, where the logical product

$$(N_1' + S_{59}) C_e$$

is generated, thus forming input n_1 to flip-flop M_1 .

It will be recalled from FIG. 2 that print control circuit 124 operates, on receipt of a start pulse S from the computer, to produce a series of pulses $N_1 C_e$ which is fed to character counter 125, which, in turn, responds by changing its output from quiescent count S_x to commence counting through its cycle. Print control circuit 124 comprises flip-flops N_1 , P_1 , and Q_1 and their associated triggering networks shown in FIGS. 9 to 11, inclusive, and the network shown in FIG. 14.

From FIG. 11, the equation $q_1 = S$ indicates that flip-flop Q_1 is set true by a start pulse S , emitted by computer 90 on entering its print routine. It will become apparent in the following discussion that, as long as this flip-flop remains false, printing is not done. Thus printer 100 may be considered to be quiescent when flip-flop Q_1 is in the false state. The equation $q_1 = S_{59} C_e$ operates to set flip-flop Q_1 false when the last character of a line is printed, thereby returning the printer to the quiescent state.

The equations $n_1 = N_1 Q_1 M_1' C_g$ and $n_1 = N_1' Q_1 M_1' C_g$ of FIG. 9 indicate that the state of flip-flop N_1' is determined by the state of flip-flop Q_1 at the fall of a pulse C_g ,

which, it will be recalled, is generated once each revolution of drum 101. Output M_1' of flip-flop M_1 appears in the equations to prevent triggering of flip-flop N_1 unless bar #1 has been selected. This will be reconsidered at a later time in connection with a discussion of bar selector circuit 129. In summary, flip-flop N_1 is set true by the next pulse C_g following the receipt of start pulse S and remains true until set false by the pulse C_g following the printing of the last character of a line, i.e., after two revolutions of drum 101.

Referring now to FIG. 14, the true output N_1 of flip-flop N_1 is seen to be combined in an "and" gate with pulse C_e to form the logical product $N_1 C_e$, representing a pulse which is generated 35 times for each revolution of drum 101. These pulses are fed to character counter 125 (FIG. 2), which is triggered thereby to produce its cyclical output counts.

As indicated in connection with FIG. 2, transfer circuit 128 emits the pulse R on line 94 informing computer 90 that printer 100 is ready to receive the next character code, and thus causes flip-flops L_1 to L_6 to be reset. The circuit is shown in FIG. 17 to comprise logical "or" gate 290 which sums the selected outputs S_0 , S_1 , . . . S_{58} , S_x of character counter 125 to form the term S_a ; and logical "and" circuit 291 in FIG. 16 which generates signal pulses: $R = S_a N_1 C_e$. The selected outputs of character counter 125 used to form term S_a will be further discussed with reference to FIG. 30, and it will be shown that the selected outputs are individually effective to time the transmission of a pulse R to computer 90.

The action of deflection circuits 131 and 136 will next be discussed.

With reference to FIG. 2, both deflection circuits generate voltages which affect beam 146 of tube 132 at the position on screen 134 determined in the vertical direction by the setting of flip-flops L_1 to L_3 and in the horizontal direction by the setting of flip-flops L_4 to L_6 .

Vertical deflection circuit 136 generates ten linear vertical sweep voltages for beam 146, one to correspond to each of the ten C_s pulses received during the time when the ten projections 107 corresponding to a character are traversing recording bar #1 or #2. The sweep voltages are of equal amplitude and period and, as shown in the enlargement of a portion of screen 134 of FIG. 23, the beam traces which they produce are displaced from each other an incremental distance as determined by horizontal displacement voltages generated by horizontal deflection circuit 131.

Returning to FIG. 2, horizontal deflection circuit 131 generates ten incremental displacement voltages for beam 146, one to correspond to each of the ten count outputs T_0 to T_9 , received from sweep counter 126. These voltages are D.C. and operate to position sweeps generated by vertical deflection circuit 136 small incremental horizontal distances such that the first sweep (see FIG. 23) generated for a character is positioned near the left side of the character area, the second is positioned to the right of the first, etc., the tenth sweep being positioned near the right side of the character area.

Screen 134 may be considered to be divided so as to accommodate, in its central portion, a square raster comprised of 64 smaller character area rasters 133. For convenience, character area rasters 133 may be laid out in an eight by eight matrix, the columns corresponding to vertical deflection of beam 146 and the rows corresponding to horizontal deflection of beam 146, and may be referenced to mask 135 shown in FIG. 20. It follows that output from vertical deflection circuit 136 (FIG. 2) will position beam 146 at a row (FIG. 20) and that the output from horizontal deflection circuit 131 will position beam 146 at a column (FIG. 20). Thus beam 146 will be positioned to a particular character area, the selection being a function of the states of flip-flops L_1 to L_6 . The selection is illustrated in FIG. 21, where it is seen that, since flip-flops L_1 to L_3 feed into vertical deflection circuit 136,

13

they are termed row selectors; and, since flip-flops L4 to L6 feed into horizontal deflection circuit 131, they are termed column selectors. To illustrate, if the code set up in flip-flops L1 to L6 is 010 000 (20), beam 146 will produce a raster 133 covering the character area on which row 2 and column 0 converge (FIG. 20).

Returning momentarily to FIG. 23, a portion of screen 134 and the appearance of a raster 133 thereon, the sweep voltage generated by vertical deflection circuit 136, in response to each pulse C_s received (FIG. 2), will cause the beam to deflect once from the top of the character area to the bottom. The displacement voltage generated by horizontal deflection circuit 136, in response to each count output of sweep counter 126, will shift the beam to the right of a prior position. Thus, for output count T_0 , the first sweep will occur near the left side of the character area; for output count T_1 , the second sweep will occur a small incremental distance to the right of the first, etc.; and for output count T_9 , the tenth sweep will occur near the right side of the character area.

The circuitry comprising deflection circuits 131 and 136 is shown in FIGS. 18 and 19, and will now be described in detail.

Referring first to FIG. 18, a schematic diagram of horizontal deflection circuit 131, it is seen that two groups of signal input are provided: one group comprising the outputs of flip-flops B1 to B4 of sweep counter 126, and the second group comprising the outputs of flip-flops L4 to L6 of output register 92. The two groups of inputs are connected to two deflection registers 303 and 304, inputs B1 to B4 and their primes being connected to deflection register 303 and inputs L4 to L6 and their primes being connected to deflection register 304. Each deflection register produces a pair of current outputs, via lines 306 and 307, these lines being connected as inputs to deflection output circuit 316. The horizontal deflection plates of cathode ray tube 132 are connected to the output of deflection output circuit 316.

With regard to circuitry and operation, deflection registers 303 and 304 are essentially identical; only the latter will now be specifically described.

Deflection register 304 comprises three current switch stages 308, 309, and 310, each, in turn, comprising dual tubes, such as 308a and 308b, in identical circuit arrangements.

Referring particularly to current switch stage 308, the driving voltage therefor is input L₄', which, as has been noted, may be at either +125 v. or +100 v., but which is characterized by slight variation in voltage due to drift of D.C. level. Input L₄' is coupled to the grid of tube 308a by way of resistor-capacitor parallel network 311 and grid resistor 312, the two resistors serving as a voltage divider to reduce the amplitude of the 25 volt excursions of input to a level appropriate for driving the tube. Clamping diode 313 serves to clamp the grid of tube 308a at ground potential, thereby overcoming any positive drift voltage from spuriously triggering the tube.

14

are connected to lines 306 and 307, respectively, in common with all other current switch stages of deflection registers 303 and 304. Lines 306 and 307 are connected to the cathodes of tubes 315a and 315b, respectively, of deflection output stage 315; thus these tube circuits serve as plate loads for the stages of the horizontal deflection registers.

It may be noted that, in the preferred arrangement of both deflection registers 303 and 304, succeeding current switch stages have a geometric progression of value of cathode resistor, i.e., for deflection register 304, resistor 314 is twice the value of resistor 314a and resistor 314a is twice the value of resistor 314b. Thus stage 308 has twice the effect on deflection as stage 309 and stage 309 has twice the effect on deflection as stage 310.

Since input L₄' is coupled to the grid of tube 308a and input L₄ is coupled to the grid of tube 308b, and due to the cathode intercoupling, only one of the tubes 308a and 308b can conduct at a time, it should be apparent that current switch stage 308 "follows" the state of flip-flop L4, tending to raise the voltage level of line 306 and lower the voltage level of line 307 when flip-flop L4 is true and, conversely, tending to lower the voltage level of line 306 and raise the voltage level of line 307, when flip-flop L4 is false. The other stages of deflection registers 303 and 304 act similarly with regard to their respective flip-flop sources of input and lines 306 and 307.

The currents drawn by tubes 308a, 309a, and 310a of deflection register 304 add via line 306, and the currents drawn by tubes 308b, 309b, and 310b add via line 307. Table II presents typical values of current drawn for deflection register 304 per se. The orderly progression of currents drawn through lines 306 and 307, comprising the sum of currents through tubes 308a, 309a, 310a and 308b, 309b, 310b, respectively, as a result of changes in the combinational state of flip-flops L4 to L6 and the geometric progression of cathode resistors, is apparent.

It is noted, for instance, that a relatively large change of current through tube 308, 20 ma., is caused by a change of state of flip-flop L4. This large change would tend to alter the plate potential, as provided by line 306, of tubes 309a and 310a which are also connected to line 306. It follows that a subsequent change in the state of flip-flop L6 may be of reduced effectiveness, due to this alteration in plate potential.

The function of tubes 315a and 315b is to limit the voltage alteration at the plates of the switch tubes due to any change in the combinational state of flip-flops L4 to L6. As shown, the plates and grids of tubes 315a and 315b are both returned to fixed positive potentials and input to the tubes is by way of the cathodes, which are connected to lines 306 and 307, respectively. Thus, by serial inclusion of the control tubes in the plate circuits of the switch tubes, any variation in potential level of the plates of the latter due to signal impression is effectively reduced in ratio of the gain of the former.

TABLE II

Computer Output Register Flip-Flops			Switch Stage Tube Current						Output Current	
L4	L5	L6	308a, ma.	308b, ma.	309a, ma.	309b, ma.	310a, ma.	310b, ma.	Line 306, ma.	Line 307, ma.

The cathode of tubes 308a and 308b are intercoupled by means of common cathode resistor 314 and the plates

Horizontal deflection of beam 146 is a function of the difference of potential between the plate outputs of

stage 315 of deflection output circuit 316, i.e., there is a unique magnitude of potential difference corresponding to each of the eight positions of beam 146 caused by the eight possible combinations of the states of flip-flops L4 to L6, and, effectively adding thereto, a unique slight variation in magnitude of potential difference corresponding to each of the ten positions of beam 146 caused by the ten combinations (T₀ to T₉) of the states of flip-flops B1 to B4. Thus deflection registers 303 and 304 provide a unique voltage output at the deflection plates of tube 132 in accordance with the code of the parallel input signals B₁ to B₄ and L₄ to L₆ and their primes.

Provisions are further made for initial adjustment for width of the raster and for beam positioning. The former provision is made by potentiometer 319, connected to the plate outputs of deflection output stage 315 so as to permit simultaneous variation in impedance between each plate and the +550 v. source. Adjustment of potentiometer 319 alters the magnitude of beam horizontal deflection for a given value of current drawn by tubes 315a and 315b without changing the average potential between the deflection plates. Beam positioning is provided by deflection control stage 317, the plate outputs of which connect to lines 306 and 307 in parallel with the outputs of deflection registers 303 and 304. Potentiometer 320 here controls the balance of currents through control tubes 317a and 317b to shift beam 146 in a horizontal direction.

As stated, for each setting of flip-flops L4, L5, and L6 resulting in one of eight current output conditions on lines 306 and 307, ten relatively small additive current outputs are provided on these lines by the ten discrete settings of flip-flops B1 to B4 of sweep counter 126 shown in Table I. As is evident, the symmetry of the combinational codes set up sequentially in flip-flops B1 to B4 provides for incremental current outputs on lines 306 and 307 and minimizes the extent of change in the combinational state of these flip-flops.

Referring next to FIG. 19, a schematic diagram of vertical deflection circuit 136, it is apparent that deflection register 305 comprises an arrangement identical with deflection registers 303 and 304 of FIG. 18, except that the outputs of flip-flops L1, L2, and L3 are employed, and deflection output circuit 318 comprises an arrangement identical with deflection output circuit 316 of FIG. 18.

In order to effect vertical scanning, it is of course necessary that the timewise deflection of beam 146 (FIG. 2) be linear, thereby necessitating a difference of potential between the vertical deflection plates of tube 132 which increases linearly with time and retraces rapidly at the termination of a scan. Thus the scan voltage must have a sawtooth waveform. It should also be apparent that a vertical scan must occur during the time interval between successive pulse C_s, during which time period a character section is printed, as will be shown hereinafter.

Utilizing pulse C_s, vertical sweep circuit 321 produces a push-pull sawtooth waveform of voltage which is applied on lines 333 and 334 in parallel with the outputs of deflection register 305 and deflection control stage 322 to deflect beam 146 in the vertical direction.

Vertical sweep circuit 321 comprises discharge stage 323, connected as a cathode-follower, direct-coupled to phase inverter 324. Capacitor 325 connected between the cathode of discharge tube 323 and ground, resistor 326 connected between the cathode and the -300 v. supply, and tube 323 comprise the charge-discharge circuit in which the desired sawtooth sweep waveform originates.

Phase inverter 324 is of the cathode-coupled type wherein tubes 324a and 324b are intercoupled by means of common cathode resistor 327. Signal input applied to the grid of tube 324a appears inverted at the plate and in phase at the cathode. No inversion of signal occurs

in tube 324b and thus the plate outputs of tubes 324a and 324b are inverted images.

Pulse C_s will be shown at a later time to be a rectangular wave, approximately 5 microseconds in duration with about a 140 microsecond period, in the preferred embodiment of the printer. During the 135 microsecond interval between pulses, discharge stage 323 is cut off and capacitor 325 starts to accumulate charge from the -300 v. supply through resistor 326. Charging of capacitor 325 is interrupted by a pulse C_s, during which discharge stage 323 conducts, and the accumulated charge of capacitor 325 is dissipated. The time constants of the charge-discharge paths for capacitor 325 are so chosen that charging is linear and discharge is rapid. Network 328 is provided to couple any D.C. level change appearing on the grid of tube 324a to the grid of tube 324b, thereby precluding any unbalance due to accumulated charge on one of the grids.

Positioned adjacent screen 134 (FIG. 2) such that their surfaces adjoin is provided mask 135, shown in FIG. 20. As with screen 134, mask 135 may be considered to be divided so as to accommodate, in its central portion, 64 character areas. Mask 135 is opaque to light except in a character area made translucent in the outline of a character. Mask 135 is fitted to screen 134 such that the row and columnar divisions shown correspond. Thus a row and column selection made by flip-flops L1 to L6 causes beam 146 of tube 132 to illuminate, in accordance with the scan and sweep already described, the character outlined at the selected position. It will, of course, be recalled that the code, as set up in flip-flops L1 to L6, need not represent, in computer language, the character actually outlined on mask 135 at the convergence of the selected row and column. For instance, using the example cited above, concerning the code 010 000 (20) set up in flip-flops L1 to L6 and calling for beam deflection to the character area at row 2, column 0, it is seen from FIG. 20 that the character "A" is selected. Using a mask containing a different distribution or assortment of characters, the code 010 000 might select a different character for printing, or none if the character area is blank, thus causing a space to be left on paper 114. It is this feature, namely, the use of different mask configurations and the resulting difference in language between computer 90 and printer 100, that adapts the system of the present invention to substitution coding techniques.

FIG. 22 shows an enlarged view of the area of mask 135 marked in FIG. 20, and also shows the coverage of the characters "A" and "9" by character area raster 133 (FIG. 23).

With regard to the configuration of the individual characters on mask 135, the enlargement indicates a stepwise arrangement in their formation. The character, in the present embodiment, is preferably not roundly formed, but columnarly divided into ten vertical sections, the stepwise arrangement prevailing between adjacent sections. The voltage supplies for cathode ray tube 132 are fixed to provide a beam narrower than a section, and the scans in raster 133 overlap to a slight extent at top and bottom of the area of mask 135 which may be occupied by a character. This overlap corresponds to the difference in distance between separation of projections 107 (FIG. 3) and width of apex 153 (FIG. 5) of bar #1 or #2, i.e., beam 146 (FIG. 2) is unblanked by pulse C_s slightly before a projection 107 is positioned below a recording bar and is again blanked slightly after the projection has passed the bar. Thus it is assured that beam 146 is unblanked during the entire period for which a scan occurs. The step arrangement device allows a degree of tolerance in horizontal drift without affecting light output. It should be noted that this also provides for rapid change in light intensity output as a scan tra-

verses opaque and transluscent portions comprising a section.

Referring next to FIG. 24, a further enlargement of the character area of FIG. 22, it is readily seen that the character is identified by regions 137 of relatively abundant illumination, corresponding to the translucent character outline, and by regions 138 of little or no illumination, corresponding to the opaque portions of mask 135. Since the impingement of electron beam 146 on screen 134 produces a circular spot and it is this spot which accomplishes the scanning, it should be apparent that the light output through mask 135 does not appear and extinguish abruptly as the spot enters and leaves a translucent region.

Returning again to FIG. 2, it is noted that the illumination passed by mask 135 is observed by phototube 139. The voltage output of phototube 139 is proportional to the intensity of illumination on its sensitized cathode 141, and considering the output voltage when electron beam 146 is at region 138 (FIG. 24) of small illumination as a reference, assigned a value of 0 volt, the output voltage, when electron beam 146 is at region 137 of abundant illumination is about -3 volts. FIG. 26 shows the voltage output waveform of phototube 139 for each of the ten scans covering the CRT screen area underlying the character "A" on mask 135. The set of waveforms graphically represents the set of electric pulse trains representing character A.

The voltage output of phototube 139 has a pulse waveform, the negative-going excursions of which are of varying duration depending on the time interval for which beam 146 is traversing region 137. Assuming that drum 101 of the preferred embodiment rotates at 20 revolutions per second, the time taken per revolution is thus 50 milliseconds. During this time 35 signal pulses C_e are generated. Since each signal pulse C_e initiates the printing of a character, it follows that about 1.4 milliseconds are required to print a character. It further follows that 140 microseconds are required for each of the ten scans per character on mask 135, including retrace time. The character configuration on mask 135 is chosen such that the time interval for the shortest output, designated t , from phototube 139, corresponding to an area 137 of height d in FIG. 24, is $\frac{1}{20}$ of the time interval for the longest output, corresponding to an area 137 of maximum height. The time interval t is thus about 5 microseconds and, obviously, the time interval for the longest output is 140 microseconds. It may be noted from FIG. 2 that the prime voltage of signal C_s , namely C_s' , is employed as an unblanking signal at the control grid of tube 132 to turn on beam 146 during the trace time interval.

FIG. 25 presents an enlargement of a portion of paper 114 containing an ultimate recording. The stepwise arrangement in character formation is evident.

With reference next to FIG. 27, phototube 139 is of the photomultiplier type having a plurality of sensitized metal electrodes 140 arranged, by proper choice of supply potentials, to attract photoelectrons emitted from photocathode 141 as a result of impingement of incident light. Due to the phenomenon of secondary emission from electrodes 140 and a physical arrangement which provides serial transmission of photoelectrons from one electrode to the next, an appreciable current flows through collector 143 and, in the present embodiment, provides a voltage on the order of -3 volts at the grid of amplifier tube 145 for maximum intensity of light through mask 135. Assuming that electron beam 146 of cathode ray tube 132 has just scanned an area 137 (FIG. 24) of height d , thereby producing an intense light output through mask 135 for a time interval t (FIG. 26), pulse 147 will represent the input to amplifier 145. The output of amplifier 145 is pulse 148 and is coupled to limiter 149. Limiter 149 is normally cut off but is easily driven to saturation by pulse 148 to produce pulse 150 clamped between the voltage levels +100 v. and +125 v. Pulse

150 is coupled to a further limiter 151 for inversion and further squaring. The output of limiter 151, designated signal I, is thus a squared voltage pulse of duration t clamped at the +100 v. and +125 v. levels, and appears on line 152 which connects to bar selector circuit 129 (FIG. 2).

It has already been pointed out that, in the preferred form, printer 100 employs two magnetic recording heads, designated, in FIG. 2, bar #1 and bar #2, which cooperate with recording projections 107 along a helical path of drum 101 to magnetize paper 114. The magnetization is in accordance with information I, arranged in electrical pulse form by signal shaping circuit 158, and conveyed to bar selector circuit 129.

Bar selector circuit 129 provides two outputs, one to each of a pair of driver circuits, which operate to supply magnetizing current for the bars. It is the function of bar selector circuit 129 to select between the outputs in accordance with the bar to be energized: if the first 30 characters are to be recorded, bar #1 is selected; if the last 30 characters are to be recorded, bar #2 is selected.

Bar selector circuit 129, shown in FIG. 28, comprises three "and" circuits 184, 185, and 186 and includes flip-flop M1, shown in FIG. 12. "And" circuit 184 receives the inputs S_{0-59} , I, and N_1 and forms the logical product $S_{0-59}IN_1$. The input S_{0-59} is high (+125 v.) when a count set up in character counter 125 is in the group from S_0 to S_{59} ; this term, if low, thus precludes printing although a recording projection 107 is traversing below a bar. The signal I represents the information to be printed, as already shown in connection with FIG. 27. The term N_1 represents the true output of flip-flop N1, which is high only during the printing cycle, and thus precludes printing at any other time.

35 The actual selection between bar #1 and bar #2 is a function of the state of flip-flop M1, shown in FIG. 12. It is seen that this flip-flop is triggered false (output M_1' is high) at count S_{59} and triggered true (output M_1 is high) at count S_{29} . Thus output M_1' will become high just before the first 30 characters of a line are to be printed (using bar #1) and output M_1 will become high just before the last 30 characters of a line are to be printed (using bar #2). The selection is accomplished in "and" circuits 185 and 186 of FIG. 28, the former of which permits gating through to bar #1 driver circuit when output M_1' is high, and the latter of which permits gating through to bar #2 driver circuit when output M_1 is high.

The two bar driver circuits are identical and, with reference to bar #1 driver circuit of FIG. 28, comprise voltage amplifier 183, cathode follower 187, voltage amplifier 188, cathode follower 189, and a plurality of paralleled power amplifiers 190, connected serially in the order mentioned with reference to the signal. Coil 113 of bar #1 provides the plate load for power amplifiers 190. 55 These circuits are well known in the art and will not be further described.

Again referring to FIG. 2, the medium contemplated for use with the present printer is roll paper 114 approximately 10½ inches wide having a magnetizable surface such as an iron oxide coating on one side. Paper 114 is threaded horizontally between the recording bars (#1 and #2) and drum 101, with its sensitized surface facing the latter, then under shaft 115, thence vertically over idler shaft 119.

60 Paper move circuit 157 is shown schematically in FIG. 29 to comprise a two-stage amplifier of conventional design. Input to amplifier 159 is output P_1' from flip-flop P1 (FIG. 10) of print control circuit 124, which falls to +100 v. after the last character of a line has been printed, as will be shown in a discussion of the graphs of FIG. 30, and rises to +125 v. at the end of the printing cycle. The output of amplifier 159 is a reproduction of the input, although inverted, and is directly coupled to power amplifier 160. The plate load for power amplifier 160 comprises coils 161 of relays 120 connected

serially. Relays 120 are identical and are of the solenoid actuator type, arranged through linkages 121 to cause abrupt horizontal motion to support yokes 123 of free-rolling rollers 122. When output P_1 of flip-flop P_1 is low, relays 120 are energized by paper move circuit 157 and rollers 122 press paper 114 against continuously rotating shaft 115, thereby almost instantaneously setting paper 114 in motion in the direction of the arrow shown.

Referring next to FIG. 31, paper 114 is seen to be guided to form a loop by free rollers 193, 194, and 195, then passes through dusting chamber 179 by way of slots 196 and 197, thence past drier 182 to take-up mechanism 202, after which it is collected in a collector bin (not shown).

With reference to paper 114, it may be noted that provision may be made to permit service as an offset printing master by incorporating, in manufacture, a white, diffusely reflecting, water acceptable top coating, without hindrance in any respect to service as a magnetic recording medium.

The operation of printer 100 with respect to computer 90 will next be discussed with particular reference to FIG. 30, which graphically displays the time sequence of activity of printer components. It will be convenient to assume passage of time in the direction of the arrow at the top of the figure. Further, a drum revolution will be considered to start at the time when the trailing edge of pulse C_g is generated, as indicated in line I. Pulses C_g and C_s are shown in lines II and III, respectively. Their relationship to each other and to pulse C_g and the correspondence of the three clock pulses to projections 106 of FIG. 3, are evident from the previous discussion.

For convenience of presentation, portions of the activity during the two successive drum revolutions comprising a printing cycle, together with portions of the drum revolutions preceding and following this printing cycle, have been extracted from the continuous graphs describing the printing operation. These portions are numbered consecutively from 261 to 266 as identified at the bottom of the figure.

The quiescent state of the printer may be considered as a condition in which power is supplied such that drum 101 is revolving, the three clock pulses C_g , C_c , and C_s are being generated, all flip-flops (Q_1 , N_1 , M_1 , and P_1) are in the false state, character counter 125 is set at output S_x and sweep counter is providing its count outputs T_0 to T_9 sequentially. It will be assumed that at some previous time, characters have been printed, the last being the character "A," the printer then becoming quiescent. Thus, since the last code set up in flip-flops L1 to L6 of computer 90 corresponded to this character, it should be obvious that, prior to the time of the fall of pulse C_g in portion 261 of FIG. 30, the states of the switch stages of deflection circuits 131 and 136 (FIGS. 18 and 19) are set to cause deflection of beam 146 of cathode ray tube 132 to the character area of mask 135 in which the character "A" is outlined (FIG. 2). Since sweep counter 126 is operating, this character area will continue to be scanned by beam 146 repetitively. Also, since pulses C_s are being generated, beam 146 will be appropriately unblanked and thus, for each scan of the entire character area, the train of signals shown in FIG. 26 will issue from phototube 139 and be shaped by the circuit of FIG. 27 to comprise a series of pulses I of varying duration corresponding to the character outline. The pulses I will be fed as one input to "and" gate 184 of bar selector circuit 129 (FIG. 28). However, since the other two inputs to "and" gate 184, namely S_{0-59} and N_1 , are low in voltage (at +100 v.), the former due to the fact that, as stated, character counter 125 is at the count S_x , and the latter due to the fact that, as stated, flip-flop N_1 is false, the product $S_{0-59}N_1$ is also low. It follows that no effective input is provided for the bar driver circuits #1 and #2, the recording bars are not being energized, and thus no recording is being made. Further, the false state

of flip-flop M_1 readies bar #1 for energization by output from "and" gate 184 since the term M_1' is an input to "and" gate 185, the latter providing input to the bar #1 driver circuit.

Since drum 101 is in continuous rotation, the receipt of signal S may occur at any time during a revolution. The next two complete revolutions following the receipt of signal S may be designated as a printing cycle, during which the printing of one line of 60 characters on paper 114 is accomplished and paper 114 is moved in preparation for printing an additional line.

The only effect of the receipt of signal S, with respect to the time prior to the start of the printing cycle, is to set flip-flop Q_1 true as indicated at line IV of FIG. 30.

15 The subsequent fall of pulse C_g sets flip-flop N_1 true (line V) by operation of the equation $n_1 = N_1'Q_1M_1'C_g$ (FIG. 9). During the time that pulse C_g is high, the equation $R = S_xN_1C_g$ (S_x , from FIG. 17, is in this case S_x) is effective to cause transfer circuit 126 (FIG. 16) to signal program counter 91 that printer 100 is ready for a

20 reset of flip-flops L1 to L6 (FIG. 2). The computer program therefore advances to reset these flip-flops; it is noted that this is accomplished prior to the generation of the succeeding pulse C_s . Deflection circuits 131 and 136 are set up to correspond with the new code and beam 146 is deflected to the top right of the selected character area. The fall of pulse C_g also causes the output S_0 to be set up in character counter 125 (line VI). Although the spot actually is unblanked at this time (line XI), phototube 139 receives no illumination since the spot is positioned under a dark area of mask 135. It follows that there is no input I to bar selector circuit 129 (FIG. 28). Also the first recording projection 107 of the helical path (FIG. 3) is outside the area in which it may affect the

result of the generation of the pulse $R=S_0N_1C_c$ (line VII).

Portion 263 of the graph of FIG. 30 shows the completion of the scanning of the 30th character and the beginning of the scanning of the 31st. It will be recalled from the discussion of FIG. 3 that bar #1 is employed for the recording of the first 30 characters of a line and bar #2 is employed for the recording of the second 30 characters. Switching between bars is accomplished by bar selector circuit 129 (FIG. 28), particularly as a function of the state of flip-flop M1 thereof. Thus energization of bar #2 driver circuit occurs when flip-flop M1 goes true as directed by the equation $m_1=S_{29}C_c$ (FIG. 12). This change is accordingly shown in line VIII of FIG. 30. Other activity during portion 263 has already been described.

Portion 264 of the graph occurs at the end of the first revolution of the printing cycle which is coincident with the end of the printing of the 35th character in the printing process. The precise positioning of recording projections 107 in the helical path permits the start of the printing of the 36th character with the second revolution of the printing cycle, immediately upon the end of the printing of the 35th character.

Portion 265 of the graph shows the end of printing for this printing cycle. It will be noted that the output of character counter 125 changes from S_{59} to S_x (line VI). The term $S_{59}C_c$ appears in the equations for setting flip-flops Q1 and M1 false (FIGS. 11 and 12, respectively), this action being shown in lines IV and VIII, and in the equation for setting flip-flop P1 true (FIG. 10), this action being shown in line IX. The false state of flip-flop M1 readies bar #1 (FIG. 28) as already outlined. The true state of flip-flop P1 provides signal input to paper move circuit 157 (FIG. 29) energizing relays 120 and thereby causing paper 114 to move. The motion of paper 114 continues for the ten character-time interval remaining in this revolution (FIG. 3) which suffices to position to a new line, and is halted during portion 266 when flip-flop P1 is reset to the false state by operation of the equation $\phi P_1=M_1' C_g$ (FIG. 10). Also with the fall of pulse C_g , flip-flop N1 is reset false: $\phi n_1=N_1 Q_1' M_1' C_g$ (FIG. 9). Printer 100 is now ready to receive the next start pulse S from computer 90. It may be noted, however, that, if an additional pulse S were transmitted prior to the end of this printing cycle, it would be effective only to set flip-flop Q1 true if received after the fall of the pulse C_g in portion 265. Under this condition, sequential printing cycles can occur for successive two-revolution cycles of the drum.

The inking system shown in FIG. 31 will next be described. Tests have indicated that a low velocity cloud of ink near the paper 114 produces the best image with the least background. Thus, as schematically illustrated in FIG. 31, the sensitized surface of paper 114 is contacted by a low velocity cloud 181 of magnetic particles, such as iron oxide, supplied in a continuous stream through duct 180a from reservoir 198. Blower 200 driven by motor 199 feeds the air stream under pressure into the reservoir 198 which comprises a venturi 221 into which the particles from duct 180b are metered by valve 219. Cyclone separator 220 separates returning particles in duct 180 from the air stream, the particles being redeposited in duct 180b, and the clean air stream being conveyed to blower 200 by way of duct 180c. The magnetic particles are coated with a thermosetting resin and are on the order of 3 to 7 microns in size. These particles are attracted to paper 114 to form a dense accumulation on the magnetized areas thereof so as to render the outline of the characters visible.

It should be noted that a closed loop system is used so that the loss of particles is held to a minimum. Further, the cyclone separator 220 keeps the bulk of the particles from circulating through and damaging the blower 200. The metering valve 219 allows control of the amount of

ink particles to be put back into the air stream. The system, when operated with the metering valve 219 closed, clears the passages of ink and deposits it in the lower part of the cyclone for shutdown storage.

It should also be noted that an alternative arrangement of the inking equipment provides for directing the air stream vertically upward through the dusting chamber 179 for a more even distribution of the cloud about the paper.

Drier 182 serves to heat the surface of paper 114 to which the magnetized particles are clinging, thereby melting the resin coating to a gluelike consistency. On cooling, permanent bond of the particles to the surface results.

Basically, drier 182 comprises lamp 201, of the infrared type, suitably mounted and thermostatically controlled to provide an appropriate amount of heat. It may be noted that other means of applying a controlled amount of heat, such as an induction furnace or hot plate, may be used without deleteriously affecting the print.

Still referring to FIG. 31, paper take-up mechanism 202 operates to take up any slack in the loop formed under roller 194. Take-up mechanism 202 is detailed in FIG. 32 as having friction clutch 203 which acts to convey rotational torque from shaft 204 to shaft 205, the former being constantly driven by motor 206. Friction clutch

203 is of the electromagnetic type wherein voltage applied to coil 191 produces a field which attracts armature plate 209 to contact rotor 210, the frictional forces therebetween being sufficient to convey rotational torque from rotor 210 to armature 209, and thus to shaft 205. Attached to shaft 205 is roller 207 pressing against paper 114 and free roller 208, such that rotation of shaft 205 causes motion of paper 114 in the direction shown by the arrow.

Energization for coil 191 is by way of switch 192 (FIG. 31) which is closed when a loop is formed in paper 114 below roller 194, thereby closing the electrical circuit through coil 191 to ground.

While the form of the invention shown and described herein is admirably adapted to fulfill the objects primarily stated, it is to be understood that it is not intended to confine the invention to the one form or embodiment disclosed herein, for it is susceptible of embodiment in various other forms.

What is claimed is:

1. A read-out system for an electronic digital processor comprising: means including a converter responsive to coded information signals received from the processor, and effective to generate a series of consecutive electrical signals each representing a respective portion of the shape of the information character represented by the 50 coded information signals; an electromagnetic recorder bar means receiving and energized by said series of consecutive electrical signals; means for positioning a magnetizable paper next to said bar; and a rotating drum having a plurality of spirally arranged, spaced-apart recording 55 projections provided on the surface thereof, said recording projections arranged to traverse past said magnetizable paper one at a time as said drum revolves so as to shift the concentration of the magnetic field induced in the bar by the said series of consecutive electrical signals, to thereby 60 provide a magnetic representation of each character portion side by side on the magnetizable paper.

2. A system for recording the output of an electronic digital processor onto a magnetizable paper, comprising: a register for coded signals responsive to the output of the processor; a cathode ray tube having a beam and provided on the face thereof with a character mask having an opaque background and translucent characters with each character overlying a respective character area of the tube face; control means operable to deflect the beam of said tube to cause it to scan successive lineal sections of a character area selected by coded signals received by said register; means including a photocell for generating electrical signals in response to the modulated light passed 70 through said mask as a character area is sectionally

scanned; an electromagnetic recording bar; a rotatable drum provided with a timing signal track; means including a reading device cooperating with said track to generate timing signals; and a plurality of recording points helically disposed about the surface of said drum and each movable in a respective path past said recording bar and arranged to pass said bar one at a time coincident with the generation of respective timing signals from the timing track; and means whereby said timing signals are effective to initiate a deflection scan for the beam, whereby an image of the character is formed on the paper.

3. A system for recording the characters represented by coded binary signals comprised in the output of an electronic digital data-processor, onto a magnetizable paper, said system comprising: a cathode ray tube having a generally opaque mask on the face thereof provided with translucent portions defining characters each overlying a respective character area of the tube face; means for controlling the beam of said tube to scan a character area of the tube as selected by the coded signals; a photoelectric means for generating electrical signals in response to light passed by the mask and produced by the beam as it progressively scans the selected character area; a rotary drum having a plurality of magnetic-field concentrating projections helically disposed about the surface thereof, said drum also provided with a track of timing projections having a predefined relationship to said field concentrating projections; reading means cooperating with the timing projections of said drum to generate timing signals in response to drum rotation; an electromagnetic recording bar energized by said electrical signals, positioned adjacent said drum surface with said magnetizable paper located therebetween; and means responsive to said timing signals for timing the scanning of the selected character area by said beam such that each sweep of the character being scanned is synchronized with the traversal of a field concentrating projection past said bar.

4. A digitally controlled magnetic printing apparatus comprising: means providing coded binary signals representative of an alphanumeric symbol; means comprising a signal generating device responsive to said coded binary signals to generate groups of electric signals representing said symbol; an electromagnet having as a core an elongate bar, said electromagnet being connected to said signal generating device; means including a rotatable means having helically disposed groups of spaced-apart magnetic field concentrators, said rotatable means being arranged to move said field concentrators in circular paths and past said bar and with the axis of rotation substantially parallel with a pole face of said bar; means for advancing a magnetically sensitive record medium between said bar and said rotatable means; a plurality of timing elements disposed in a track around said rotatable means; sensing means responsive to passage of said timing elements for generating timing signals; and a synchronization circuit actuated by the timing signals from said sensing means for synchronizing the generation of each group of signals by said signal generating device with the traversal of a respective group of field concentrators past said bar.

5. Magnetic recording apparatus for coded digital signals, comprising; a mask having transparent areas and opaque areas so arranged that the transparent areas define symbols; means for providing light on one side of the mask; positioning means for controlling the position of the light relative to the mask, said positioning means controlled by the coded signals to cause the light to be provided at but one at a time of the discrete areas of said mask; a rotatable member having a timing signal track thereon; reading means for producing timing signals from said timing signal track; additional means for controlling the light, responsive to said timing signals to cause said light to serially impinge upon separate sectional portions of a selected one of said transparent areas;

photoelectric means disposed for reception of light transmitted through a transparent area, for producing electrical pulse trains corresponding to respective ones of said sectional portions; an electromagnet successively energized by the respective pulse trains and positioned adjacent the surface of said rotating member; a plurality of field concentrators on the surface of said rotating member, each arranged to traverse past a respective area of said electromagnet one at a time to serially intensify the magnetic field issue from said electromagnet at the area of traversal; and means for supporting a magnetizable record medium between said electromagnet and said rotating member such that a recording of the symbol scanned on the mask is produced on the medium.

6. Magnetic recording apparatus comprising: a magnetic recording paper; a source of sets of sequential electric pulse trains; means including an electromagnet in the form of a recording bar having an elongate pole face and connected to be energized by the pulse trains from said source; rotary means including a plurality of groups of spaced-apart magnetic field concentrators spirally situated on a cylindrical surface having an axis parallel to said electromagnet, each group of field concentrators corresponding to a respective set of the pulse trains energizing said electromagnet; means to rotate said rotary means to sequentially move said field concentrators in lineal paths past respective locations closely adjacent said electromagnet pole face to thereby intensify the electromagnetic field issuing from the electromagnet at locations along said paths adjacent said electromagnet so as to produce corresponding latent magnetic lineal images on said magnetic paper as the paper is disposed between said electromagnet and said field concentrators; and means to render the latent image on said paper visible.

7. Magnetic recording apparatus comprising: a source of sets of sequentially produced pulse trains; an electromagnet having an elongate pole face, connected to be energized by the pulse trains from said source; a plurality of groups of spaced-apart magnetic-field concentrators, each group being operative with respect to the energization of said electromagnet by a respective set of pulse trains; means to sequentially position said field concentrators to intensify the electromagnetic field issuing from successive points along the said pole face of said electromagnet; means for advancing a magnetizable paper between said electromagnet and said field concentrators whereby said paper can become magnetized with a latent image recording in accordance with the intensified field; means for dusting said paper with magnetic ink particles for rendering the latent image recordings thereon visible; and means to bond said magnetic ink particles to said paper.

8. Apparatus for recording on a record medium, symbols represented by coded electric signals, said apparatus comprising: a source of coded electric signals; signal generating means operable in dependence upon the said coded electric signals to generate electric pulse signals representative of the respective lineal configurations of successive sections of images of the represented symbols; a rotatable drum having spaced-apart projections thereon, said projections being disposed in groups and in each group disposed around the curved surface of the drum along respective helical lines; means to rotate the drum; and an electromagnetic device stationed adjacent the drum and connected to be energized by each of said electric pulse signals in turn, the projections on the drum being so arranged and the electromagnetic device being so shaped that substantially all the magnetic flux of the device when energized is concentrated by that one of the projections currently passing the device, so as to form line recordings each being a section of a magnetic record of the symbol represented by the coded electric signals.

9. Apparatus for producing on a magnetic record medium, a latent magnetic image record of an informa-

tion character represented by a set of binary coded electrical signals, comprising: means presenting a set of binary coded electrical signals representing an information character whose image is to be recorded; means including means controlled by a presented set of coded electrical signals and effective in response thereto to translate said set of coded electrical signals into a series of time-spaced sets of electrical pulses each set of which represents a vertical segment of the said character; an electromagnet means effective to receive said sets of pulses and produce during each pulse a magnetic field over a region in which a small portion of the latent image is to be produced; and means including individual moving spaced-apart ferromagnetic field-concentrating means, one for each set of said pulses and assigned to a respective portion of said region, and including means to move the field-concentrating means in succession in respective paths through said region in synchronism with the occurrence of respective ones of said sets of pulses, whereby a latent magnetic image of said character is producible on a magnetic record medium when the latter is moved through said region between said electromagnet means and the paths of said field-concentrating means.

10. Apparatus for producing on a magnetic record medium a latent magnetic image of an information character represented by a set of binary-coded electric signals, comprising: means presenting a set of binary-coded electric signals representing a character an image of which is to be recorded; translating means connected to said first-named means and effective to translate said set of binary-coded signals into a series of sets of time-separated electric pulses each set of which represents a line portion of an image of the represented character; a line connected to said translating means and on which line said series of electric pulses is impressed, and means including electromagnet means connected to said line to be energized by each of said electric pulses in its turn; and means including movable spaced-apart means for concentrating each respective magnetic field produced by said electromagnet means in response to energization by said pulses to produce a respective line of field-concentration proportional in length to the duration of the respective electric pulse for each of the pulses, and said movable means including a separate movable means for each of said set of pulses and each assigned to a different line-region of the image of said character, whereby a latent magnetic image of said character is produced upon a magnetic record medium disposed in the field-concentration regions of said movable means.

11. Magnetic recording apparatus for forming on a magnetic-sheet record medium a magnetic image of an information-character, successive laterally displaced line-portions of which image are represented by respective sets of electric pulses comprised in a series of time-spaced sets of electric pulses which together electrically represent said character, said apparatus comprising: an electrical line on which said pulses are sequentially received; an electromagnet connected to said line to be energized by said pulses within respective intervals of time, one interval for each set of pulses, and to create magnetic fields each contemporaneous with a respective pulse and all within a recording region; a set of movable spaced-apart field-concentrating means each assigned a respective line-path through the recording region and each corresponding to a respective set of said pulses; and means for moving said field-concentrating means each through its respective line-path during a respective one of said intervals of time, whereby a magnetic image of said character may be produced upon a magnetic record medium disposed between said electromagnet and said line-paths.

12. A system for forming a latent magnetic image of a character represented by a coded signal output of an electronic digital data-processor, said system comprising: a cathode-ray tube having on the face thereof a mask having areal portions assigned to respective characters and

said areal portions having opaque portions and translucent portions, the translucent portions having areal shapes and configurations of respective characters each representable by a respective coded signal output of a digital data-processor; signal-handling means including means to receive said coded signal output and in response thereto direct the cathode ray beam of said tube to an area of the screen thereof overlaid by that areal portion of the mask assigned to the character represented by the said coded signal output, and to scan that area of the screen in a plurality of successive and adjacent lineal sweeps; means including a photoelectric means arranged to receive the light transmitted through the translucent portion of the said areal portion of the mask and to produce in response thereto respective successive sets of electric pulse signals, each set corresponding to a respective lineal sweep of the cathode-ray beam; an electromagnet recording bar means arranged to receive said pulse signals and produce a respective magnetic field in response to each signal thereof; means including a plurality of movable field-concentrating means each corresponding to a respective lineal sweep of the cathode ray beam and effective during that sweep to concentrate in a respective lineal recording region in a magnetic record medium any field produced by said bar means during the respective lineal sweep of the cathode ray beam, whereby to form in the record medium a corresponding set of lineal portions of a latent magnetic image of the said character.

13. Apparatus for effecting magnetic recording of a latent magnetic image of an information character which character is represented by CRT deflection potentials effective when applied to the tube to direct the cathode-ray beam thereof to a face-area thereof assigned to the said character, said apparatus comprising: means including a CRT and deflection-potential input means therefor capable of deflecting the beam thereof to a face-area assigned to a selected character and to cause the beam to scan that area in a plurality of successive sweeps, a mask overlying the face of the CRT and provided with a translucent area overlying said face-area and having the configuration of said character, whereby as said beam scans said face-area said mask passes light which is time-modulated in accordance with lineal portions of the said translucent area of said mask; means including photoelectric means sensitive to the light passed by said mask and effective to provide electric pulses corresponding in time to the light passed by the mask; an electromagnetic recording head bar energized by said pulses to produce magnetic fields corresponding thereto; movable field-concentrating means, one for each of said plurality of successive sweeps, arranged to concentrate magnetic fields produced by said bar; and means, including means for moving said field-concentrating means each in turn past said bar, for synchronizing sweeps of said beam with movements of respective ones of said field-concentrating means past said bar, whereby to produce a latent magnetic image of said character in a magnetic record medium disposed between said bar and said field-concentrating means.

14. Magnetic recording apparatus comprising: means effective in operation to create and present successive groups of serially occurring electric pulse trains representing respective information-characters latent magnetic images of which are to be recorded; an electromagnetic recording head connected to be energized by the said pulse trains; a plurality of groups of spaced-apart field-concentrators each group of which is disposed in an echelon arrangement; means to move said field-concentrators serially past said head, each group contemporaneously with a respective one of said pulse trains, to intensify magnetic fields issuing from said head at the lines of passage of the field-concentrators; and means for synchronizing the presentation of successive groups of said electric pulse trains with passage of respective groups of said field-concentrators past said head, whereby latent magnetic images of the said characters may be produced in

a magnetic record medium disposed in the regions wherein said fields are concentrated.

15. Magnetic recording apparatus comprising: a source of serially occurring groups of sets of electric pulse trains each set of which represents a respective character a magnetic image record of which is to be produced; means including a rotatable means having an axis and provided with a plurality of sets of spaced-apart magnetic-field-concentrators arranged generally spirally with respect to said axis and in echelon disposition within each set and each concentrator having a respective circular path and said concentrators being divided into groups; two electromagnets arranged each with a respective long narrow pole face parallel to said axle and each arranged to be passed by a respective group of said concentrators each in its turn, and each electromagnet having a respective winding; means effective to cause said electromagnets to be energized, each by a respective group of sets of said electric pulse trains and synchronously with passage therapast of a respective group of sets of magnetic-field-concentrators; and means for supporting a magnetizable record medium between said electromagnets and the paths of said magnetic-field-concentrators whereby the magnetic fields produced by said electromagnets incident to energization by said pulse signals are concentrated by said magnetic-field-concentrators along line segments defining the areal configurations of the characters represented by the pulse signals, for effecting a magnetic image record of each of the represented characters.

16. Apparatus for translating into an areal latent magnetic image of an information character successive adjacent lineal portions of the image of which character are represented by respective trains of serially occurring electric pulses comprising pulses of random lengths, a set of successively occurring character-representing pulse trains defining a respective character, said apparatus comprising: means including electromagnet means having a long narrow pole face and a winding connected to be energized by the pulses of the set of electric pulse trains and to thereby create individual magnetic fields of durations proportional to the durations of the respective pulses; means including a plurality of movable spaced-apart pointed magnetic field concentrating devices each assigned and movable along a respective lineal path extending trans-

versely across said narrow pole face to thereby concentrate respective magnetic fields of said electromagnet during traverse of said path by the respective devices, said plurality of devices inculding one such devices for each pulse train of the set thereof representing the informational character; means for moving said devices successively along their respective lineal paths transversely of said pole face, each concurrently with the occurrence of its respective pulse train; and means for positioning a magnetic record medium between said pole face and the paths of said points whereby the concentrations of said fields by said points produces latent magnetic images of successive adjacent lineal portions of the image of the represented character, to produce an areal latent magnetic image of the character.
